SAFETY LOCK

Stanley M. Mercier, Grandview, Ohio, assignor
to The Jeffrey Manufacturing Company,
Columbus, Ohio, a corporation of Ohio

Application February 1, 1927, Serial No. 165,226
Renewed March 15, 1932

18 Claims. (Cl. 188—82)

The present invention relates to certain new and useful improvements in safety locks of the class adapted to prevent reverse rotation of power shafts.

5 This invention relates particularly to an automatically acting safety lock adapted for association with the head shaft of an elevator of the endless belt and bucket type, to prevent reverse rotation of the head shaft when the actuating power is interrupted during operation of the elevator.

The especial object is to provide a safety lock, such as aforesaid, which is simple in construction, reliable in service and noiseless in operation.

15 The means whereby I attain this object are fully set forth in the following specification and illustrated in the accompanying drawings of which

Fig. 1 is an end elevation of the head portion of an elevator equipped with the devices of my invention.

20 Fig. 2 is a side elevation of the mechanism illustrated in Fig. 1.

Fig. 3 is an end elevation, partly in section and on an enlarged scale, of the safety locking device shown in Figs. 1 and 2.

Fig. 4 is a longitudinal section of the safety locking device shown in Fig. 3.

Like numerals refer to similar parts in the several figures.

30 In the drawings the numeral 1 refers to the head shaft of an elevator which is supported in the journal bearings 2 attached to the supporting timbers 3. Fixed to the head shaft 1 is the head wheel 4 of the elevator which may be a sprocket wheel, such as is shown, adapted to engage the endless chain 5, or it may be a pulley adapted to engage an endless belt, or other similar device, by which the elevator buckets 6 are carried. The elevator thus formed is of the well-known type in which the buckets 6 receive their load at the foot of the elevator, carry it upward, and discharge it centrifugally as said buckets pass around the head wheel 4. The head shaft 1 may be driven in any preferred manner suitable to the conditions under which the machine operates. For purposes of illustration I have here shown an electric motor 7 having an extension shaft 8 supported in suitable journal bearings 9 attached to the timbers 10 of the supporting frame-work. Fixed to the extension shaft 8 is a pinion 11 which engages a gear wheel 12 fixed to the head shaft 1 to drive it. The motor 7 may receive its actuating current from any convenient source of electric supply, and may be controlled in any suitable manner, but as such

devices are well understood in the art, and as they form no part in the present invention, their description and illustration is not thought to be required at this time.

During the operation of an elevator such as above described, when the electric current by which the motor 7 is actuated is interrupted, the downward pull of the load in the buckets on the ascending strand of the elevator tends to produce reversed revolution of the head shaft 1, causing the loaded buckets to travel downwardly and discharge their loads at the foot of the elevator, producing a very undesirable congestion even though no definite injury to the apparatus results. Since the electric motor and its connecting gearing offers little or no resistance to such reverse revolution of the head shaft 1, excessive speed might be developed causing serious injury to the apparatus. To prevent such catastrophes, I have provided a safety lock comprising a ratchet wheel 13, mounted concentric with the head shaft 1 and anchored against rotation therewith by an arm 14 which is secured to said ratchet wheel by the bolts 15 and is anchored to the supporting timber 3 by a suitable attachment 16. The ratchet wheel 13 is mounted in such relation with the moving parts of the elevator that the ratchet teeth 17 point in the direction of normal rotation of the head wheel 4. Fixed to the head shaft 1 adjacent the ratchet wheel 13 is a disc wheel 18 having an annular flange 19 surrounding and concentric with the ratchet wheel. On the outer edge of this annular flange 19 is an inwardly projecting flange 20. Supported at spaced intervals in suitable apertures of the flange 20 and disc 18 are a plurality of pivot pins 21 upon which are mounted the pawls 22 adapted to engage the teeth of the ratchet. The arrangement of parts above described is such that the pawls 22 above the ratchet wheel 13 tend to contact therewith under the influence of gravity. During operation of the elevator the centrifugal force generated by their rotation with the head shaft 1 is sufficient to hold the pawls 22 out of contact with the ratchet wheel 13 thereby avoiding the noise which would be produced by the trailing of the pawls over the teeth of the ratchet. The proportions of the parts are such that the annular flange 19 will engage the outer end of the pawls 22 to limit their outward movement about their pivot pins 21, thus insuring their promptly falling into contact with the ratchet wheel 13 when the revolution of the head shaft 1 is interrupted. The number and spacing of the teeth 17 upon the ratchet wheel 13, and the number and 110

spacing of the pawls 22 upon the disc wheel 18, preferably bear such relation to each other that reverse revolution of the shaft 1 through an angle equal to only a fraction of the pitch of the ratchet 5 teeth 17 will cause engagement of a pawl 22, thus insuring the arrest of the shaft 1 before such speed has been attained as will develop sufficient centrifugal force to lift the pawls 22 out of engagement with the ratchet wheel. The differential 10 or vernier arrangement of the pawls 22 relative to the teeth 17 materially reduces the shock of their engagement, and this shock may be still further reduced by the cushioning effect of a spring 23 included in the anchoring device whereby the 15 arm 14 is secured to the timber 3. As clearly shown in Figure 1, this spring 23 is attached at one end to the timber 3 and at its opposite end to the bolt 16 carried by the arm 14. The bolt 16 operates in an arcuate slot 24 in a block 25 mounted 20 on the timber 3. Thus it will be obvious that the ratchet wheel 13 or abutment member has only a limited yielding movement which is sufficient to aid in cushioning shocks upon reverse tendencies of the shaft 1. When the teeth 17 25 upon the upper part of the ratchet wheel 13 become worn in service, the bolts 21 may be withdrawn, the wheel 13 rotated through a suitable angle about the shaft 1 to bring unworn teeth to the top of the ratchet wheel, and the bolts 21 30 reinserted to secure the parts in their new relation.

It is to be understood that I do not limit myself to the precise construction here shown and described, since these devices may be subject to wide variation as to details without departure 35 from the spirit of my invention.

What I claim is:

1. In an apparatus of the class described, the 40 combination with a horizontally extending shaft, of driving means adapted to cause said shaft to revolve in one direction, means tending to produce reverse revolution of said shaft, a stationary ratchet supported concentric with said shaft, and having limited yielding movement to absorb 45 shocks and pawls carried by said shaft adapted to engage said ratchet to prevent reverse revolution of said shaft as and for the purpose set forth:

2. In an apparatus of the class described, the 50 combination with a horizontally extending shaft, of driving means adapted to cause said shaft to revolve in one direction, means tending to produce reverse revolution of said shaft, a ratchet wheel mounted upon said shaft, resilient means 55 to anchor said ratchet wheel against revolution with said shaft, and a pawl carried by said shaft adapted to engage said ratchet wheel to prevent reverse revolution of said shaft as and for the purpose set forth.

3. In an apparatus of the class described, the 60 combination with a horizontally extending shaft, of driving means adapted to cause said shaft to revolve in one direction, means tending to produce reverse revolution of said shaft, a ratchet wheel supported concentric with said shaft, means adjustable relative to said ratchet wheel and adapted to prevent its revolution with said shaft, and a pawl, carried by said shaft adapted to engage said ratchet wheel to prevent reverse revolution 65 of said shaft as and for the purpose set forth.

4. Means to arrest reverse rotation of a rotating 70 shaft, comprising an abutment member, a centrifugally controlled catch member in connection with said shaft and adapted to engage said abutment member to arrest said shaft upon

a reverse tendency of the latter, and means for permitting a limited yielding movement of said abutment member upon such engagement.

5. Means to arrest reverse rotation of a rotating shaft, comprising an orbitally moving centrifugally controlled catch member in connection with said shaft, an abutment within the orbit of said catch member, said catch member being adapted to gravitate into engagement with said abutment upon a reverse tendency of said shaft to arrest the latter, and means for permitting a limited yielding movement of said abutment upon such engagement.

6. Means to arrest reverse rotation of a rotating shaft, comprising an abutment member, a centrifugally controlled catch member in connection with said shaft and adapted to engage said abutment member to arrest said shaft upon a reverse tendency of the latter, and means for permitting a yielding movement of said abutment member upon such engagement.

7. Means to arrest reverse rotation of a rotating shaft, comprising an abutment member, a centrifugally controlled catch member in connection with said shaft and adapted to engage said abutment member to arrest said shaft upon a reverse tendency of the latter, and means for permitting a limited movement of said abutment member upon such engagement.

8. Means to arrest reverse rotation of a rotating shaft, comprising an abutment member, a centrifugally controlled catch member in connection with said shaft and adapted to engage said abutment member to arrest said shaft upon a reverse tendency of the latter, and resilient means 105 for anchoring said abutment member.

9. Means to arrest reverse rotation of a rotating shaft, comprising an abutment member, a centrifugally controlled catch member in connection with said shaft and adapted to engage said abutment member to arrest said shaft upon a reverse tendency of the latter, an arm secured 115 to said abutment member, a spring connected to said arm, and means for limiting the movement of said arm.

10. Means to arrest reverse rotation of a horizontally disposed shaft, comprising an adjustable relatively stationary abutment member, and orbitally moving centrifugal controlled catch members in connection with said shaft, at least one of 125 which is adapted to gravitate into engagement with a predetermined portion of said abutment member upon a reverse tendency of said shaft to arrest the latter, and said abutment member being adjustable to compensate for wear by said 130 catch member.

11. Means to arrest reverse rotation of a horizontally disposed shaft, comprising an adjustable relatively stationary ratchet wheel, orbitally moving centrifugal controlled catch 135 members in connection with said shaft one of which is adapted to gravitate into engagement with a predetermined portion of said ratchet wheel upon a reverse tendency of said shaft to arrest the latter, and said ratchet wheel being adjustable in a orbital path to compensate for wear thereon by said catch member.

12. Means to arrest reverse rotation of a horizontally disposed shaft, comprising an adjustable relatively stationary ratchet wheel, orbitally moving centrifugal controlled catch 145 members in connection with said shaft one of which is adapted to gravitate into engagement with a predetermined portion of said ratchet wheel upon reverse tendency of said shaft to ar- 150

- rest the latter, said catch members having a vernier arrangement relative to the teeth of said ratchet wheel, and said ratchet wheel being adjustable to compensate for wear thereon by said 5 catch member.
13. Means to arrest reverse rotation of a horizontally disposed shaft, a relatively stationary member, a ratchet wheel adjustably connected to said member, orbitally moving centrifugal controlled catch members, in connection with said shaft, one of said catch members being adapted to gravitate into engagement with a predetermined portion of said ratchet wheel upon reverse tendency of said shaft to arrest the latter, 10 and said ratchet wheel being adjustable relative to said stationary member to compensate for wear upon the ratchet wheel occasioned by said catch members.
14. Means to arrest reverse rotation of a 20 horizontally disposed shaft comprising an abutment member, a centrifugally controlled catch member in connection with said shaft and adapted to engage said abutment member to arrest said shaft upon a reverse tendency of the latter, a slotted member, an arm secured to said abutment member, and having means operating in said slotted member, and spring means for retaining said arm in predetermined relation to said slotted member.
- 30 15. Means to arrest reverse rotation of a horizontally disposed shaft comprising an abutment member, a centrifugally controlled catch member in connection with said shaft and adapted to engage said abutment member to arrest said shaft upon a reverse tendency of the latter, a stationary member having a slot, an arm secured to said abutment member and having a projection operating in said slot, and spring 40
- means connected to said arm and said stationary slotted member for retaining the arm in predetermined relation to the latter.
16. Means to arrest reverse rotation of a horizontally disposed shaft comprising a relatively stationary abutment disc loosely mounted upon said shaft, said disc having its periphery equipped with ratchet teeth, means adjustably associated with said disc for retaining the same relatively stationary upon said shaft, a wheel fixed to said shaft and having an annular flange overlapping said abutment disc, and pawls carried by said wheel beneath said flange for engagement with the ratchet teeth of said disc. 80
17. Means to arrest reverse rotation of a horizontally disposed shaft comprising a stationary abutment member, a carrier rotatable with the shaft, centrifugally controlled catch members mounted on said carrier and adapted to gravitate into engagement with the abutment member upon reverse tendency of said shaft to arrest the latter, said catch members being arranged with respect to the abutment member whereby at least one of said catch members will engage said abutment member in any position of 90 said carrier.
18. Means to arrest reverse rotation of a horizontally disposed shaft comprising a relatively stationary abutment member free of said shaft, means associated with said abutment member for preventing movement of the same with respect to said shaft, an element fixed to said shaft and having an annular flange overlapping said abutment member, and pawls carried by said element beneath said flange for engagement with said abutment member. 100
